METHOD AND APPARATUS FOR VAPORIZING
LIQUEFIED PETROLEUM GAS

Arthur C. Turner, Chilhowee, Mo.

Application July 16, 1941, Serial No. 402,637

13 Claims. (Cl. 62—1)

1

This invention relates to a method and apparatus for vaporizing liquefied petroleum gas such as butane and supplying the vapor for heating, lighting, cooking, and other purposes. Since liquefied petroleum gas pressures exist up to a degree commensurate with the temperature and since the vaporizing temperature of the liquid must be kept constantly uniform it has been the practice to store the liquefied gas in pressure containers that are buried in the ground for utilizing earth heat in maintaining the desired vaporizing temperature. However, such systems are difficult to service and it is necessary to transport the liquefied gas and empty it into the underground storage container which must be vented. Consequently much of the vapor in the storage tank is lost through the vent. Also when the heating appliances are supplied from the vapor accumulating in the storage tank, large tanks are required to provide storage of sufficient capacity for supplying adequately the demand for gas, which results in high apparatus and installation cost. Another disadvantage is that vapor collected from the entire body of liquid varies widely in calorific value.

Another method of storing liquefied petroleum gas is to retain it in liquid form and deliver the liquid to a pressure regulator which reduces pressure of the gas to the vaporizing point. These systems fail to operate satisfactorily under all weather conditions for the reason that the expansion occurs so rapidly that the refrigeration effect results in frosting over and freeze-up of the pressure regulator which interferes with the operation thereof, and in cold weather the rate of heat absorption necessary to effect vaporization of the liquid is not sufficient, with the result that liquid is delivered to the heating appliances producing fire and explosion hazards that make such systems impracticable.

Therefore, the purpose of the present invention is to provide a liquefied petroleum gas apparatus wherein the gas may be dispensed in liquid form through the use of high pressure containers or bottles which may be located above ground and readily connected to a vaporizing apparatus located below ground, the liquid feed being maintained responsive to vapor pressure contained in the expansion space provided in such bottles and acting on the surface of the liquid thereby obtaining uniform calorific value of the gas.

A further object of the invention is to provide for sufficiently rapid conduction of the earth heat to an expansion and storage coil and the pressure regulators so as to maintain the temperature above the freezing point.

A further object of the invention is to pro-

2

vide the apparatus with a settling tube for trapping condensed fuel and effect revaporization thereof so that only fuel in gaseous state can reach the fuel consuming appliances.

It is also an object of the invention to provide an additional settling tube for collecting any condensate which may accumulate in the pipe lines which connect the vaporizing equipment with the gas consuming appliances.

10 A further object of the invention is to provide a float control valve in or connected with the settling tube to close automatically the outlet thereof in case excessive amounts of liquid should pass the vaporizing equipment.

15 In accomplishing these and other objects of the invention, as hereinafter pointed out, I have provided improved structure, the preferred form of which is illustrated in the accompanying drawings, wherein:

20 Fig. 1 is a diagrammatic section through a liquefied petroleum gas apparatus embodying the features of the present invention.

25 Fig. 2 is a horizontal section through the vaporizing unit of the apparatus on the line 2—2 of Fig. 1.

30 Fig. 3 is an enlarged sectional view through the settling tube, particularly illustrating the float valve for closing the outlet when an excessive amount of liquid accumulates in the settling tube.

Fig. 4 is a fragmentary section through the upper portion of the settling tube, the safety valve and service pipe line connected therewith.

35 Fig. 5 is a fragmentary section through the blow-off valve for discharging liquid from the bottom of the settling tube.

Referring more in detail to the drawings:

40 1 designates a liquefied petroleum gas apparatus constructed and installed in accordance with the present invention for supplying a dry gaseous fuel for domestic purposes in communities where ordinary gas is not available.

45 In carrying out the invention, I provide a vaporizing apparatus whereby the liquefied petroleum gas such as butane is supplied in readily handled bottles or cylinders 2 which may be filled at a remote station, transported to the point of use, and readily connected to the vaporizing apparatus. Each bottle, therefore, includes a liquid draw-off tube 3 having its inlet 4 located near the bottom of the bottle and its discharge end extending through the top of the bottle and connected with a shut-off and control valve 5 having an outlet which is adapted for ready connection and disconnection by a union 6 with a pipe 7 leading to the vaporizing apparatus generally designated 8. The control valve 5 may also include a safety pressure release valve 9 for releasing excessive pressure accumulating in the vapor

50 55 space 10 of the bottle. The vapor space 10 not

only forms an ample expansion space for the liquefied gas responsive to change in atmospheric temperatures but provides an expandable pressure acting on the body of the liquefied gas contained in the bottle for forcibly discharging the liquefied gas through the inlet 4 of the draw-off tube for flow through the pipe 7 so that only liquid is supplied from the bottle to the vaporizing apparatus 3 and the resulting gas is of substantially uniform calorific value.

Since conversion of the liquefied gas to a vapor is commensurate with temperature and pressure, the vaporizing apparatus includes a pressure reducing regulator 11 maintained at a substantially constant temperature above the boiling point of the liquid at the pressure to which the regulator is set. I therefore provide for placement of the vaporizing apparatus below ground and utilize heat of the earth for maintaining temperature of the fuel above the boiling point at the pressure set by the regulator as I have found that the earth heat is substantially uniform throughout the seasons and for practical purposes provides sufficient heat, when properly applied, to maintain the desired vaporizing temperature.

While the earth offers sufficient heat to supply the heat of vaporization, it is difficult to transmit the heat with sufficient rapidity to prevent the refrigerating effect of the expanding fuel from freezing up of the pressure regulator and interfering with flow of the fuel. In overcoming this difficulty I provide a tank 12 which is buried in the ground 13 and adapted to contain the vaporizing and gas storage apparatus at a distance below the surface of the earth where substantially uniform temperatures are maintained throughout the seasons of the year.

In the illustrated instance the tank includes a cylindrical wall 14, a bottom 15, and an open top 16 adapted to be closed by an insulated door or closure 17 which is seated on an annular ledge 18 projecting inwardly of the wall 14. In placement of the tank, the earth is compacted into intimate contact with the wall of the tank so that the heat of the earth is readily transmitted to the tank and through the tank to the interior thereof.

Supported in the tank is an expansion and gas storage element 19 in the form of a helical coil of pipe having its upper and inlet end 20 connected with the outlet side of the pressure regulator 11, the inlet connection 21 of which is connected with the pipe 7 previously mentioned, as shown in Fig. 1. The pressure regulator is set so that the pressure of the liquefied gas flowing through the pipe 7 is reduced sufficiently to effect vaporization thereof at the temperature carried in the tank, whereby the fuel is passed into the coil 19 in vapor or gaseous form and discharged through the lower and outlet end 22 thereof through a riser pipe 23 having its upper end connected with the upper end of a settling tube 24. The settling tube 24 is of sufficient length to extend substantially to the bottom of the tank and forms a liquid collecting sump 25. The upper end of the tube is provided with a gas discharge connection 26 which includes a safety valve 27 having connection with a vent pipe 28.

Specifically, the outlet connection and safety valve includes a common fitting 29 having a gas passageway 30 connecting the settling tube with a pipe 31 leading to a low pressure control regulator 32 which reduces pressure of the gas to that suitable for use in the fuel consuming appliances.

Extending laterally of the passageway 30 is a port 33 provided with an annular seat 34 for a valve 35 which is retained seated responsive to pressure of a spring 36 bearing against a cap 37 to which is connected the vent pipe 28. The spring has sufficient capacity to maintain the valve 35 seated under safe pressures in the apparatus, but should the pressure become excessive the spring will yield to allow blow-off through the vent pipe 28. The outlet of the low pressure reducing valve is connected by a pipe 38 leading through the wall of the tank and connected with the upper end of a condensate collecting tube 39 located exteriorly of the tank and imbedded in the earth at sufficient depth so that vaporizing temperatures are maintained therein. The upper end of the condensate collecting tube is also connected with the gas supply line 40 leading upwardly to the gas consuming appliance such as a cooking stove 41.

In order to assure drainage of condensation occurring in the pipe 40, the horizontal runs thereof are sloped downwardly to the condensate collecting tube whereby any condensation drains into the tube and collects in the bottom thereof, as at 42, where it is revaporized by ground temperatures and returned as a gas to the pipe 40.

In order to provide a sufficiently rapid conduction of heat from the ground to the pressure regulator so as to avoid refrigerating effect of the expanding fuel and prevent freeze-up thereof, I fill the tank substantially to the level of the top of the regulator 11 with a heat transfer medium, such as a body of liquid, for example, water 43 which also covers the coil 19 and settling tube 24. Thus the body of water serves as a conductor for rapidly collecting and conducting heat of the earth to the vaporizing equipment so as to maintain the temperature thereof above the vaporizing point of the liquefied gas and prevent freeze-ups which might occur at times of heavy demands on the equipment. With this arrangement, the settling tube is also kept above the vaporizing temperature of the gas so that should any liquid pass the regulator 11 and collect in the bottom 45 of the settling tube 24 it will immediately be vaporized and passed off in the form of gas through the low pressure regulator 32 to the heating appliance.

In order to provide an additional safety feature and prevent flooding of the outlet pipe 40 with liquid, I have provided the outlet of the tube with a shut-off valve 44 adapted to be operated by a float 45 having connection with one arm 46 or a bell-crank lever 47 through a stem 48, the bell-crank lever being pivoted in a recess 49 of the valve body 50 on a pin 51. The other arm 52 of the bell-crank engages against a valving member 53 which is adapted to close a port 54 directly connected with the tube outlet. Thus when liquid accumulates, as shown in Fig. 3, the float rises to close the valve and prevent discharge of liquid. If, for some reason, the safety appliances above described should fail to work and liquid fuel be discharged through the pipe 38, it will be trapped in the condensate collecting tube.

In order to discharge any excessive amount of liquid that may collect in the settling tube 24, the lower end thereof is connected with a blow-off or pressure testing tube 55 extending upwardly within the tank 12 to a point above the level of the water where it is provided with a valve 56, normally retained seated responsive to a spring 57 but which is adapted to be readily unseated by

pressure applied to a plunger 58 projecting through the discharge port 59 of the valve housing 60.

In operating an apparatus constructed and installed as described, the bottles 2 containing the liquefied gas are connected with the pipe 7 by the union 6. The valve 5 is then opened so that the vapor pressure in the bottle discharges the liquefied gas through the draw-off tube to the pipe 7 where the liquefied gas flows to the high pressure regulating valve 11, the regulating valve having been set to reduce the pressure sufficiently to effect vaporization of the fuel at the temperature of the body of water contained in the tank 12. Since the heat of the earth is transmitted to the body of water with sufficient rapidity to maintain the temperature thereof above freezing throughout the seasons of the year, frost and ice are prevented from accumulating on the regulator so as not to interfere with successful operation thereof. The vapor or gas flows through the coil 19 where it is kept in gaseous state by the earth heat transmitted to the coil through the water as a conducting medium. When the gas consuming appliance is lighted, the vapor flows from the coil through the settling tube, through the low pressure regulator where the pressure is further reduced, and through the pipes 38 and 40 to the appliance. Any liquid which may pass the high pressure regulating valve 11 or condense in the coil 18 will gravitate into the bottom of the settling tube 24, leaving a dry gas to flow to the low pressure regulator and to the heating appliance. As above pointed out, any condensate occurring in the lines 38 and 40 will drain into the tube 39. Should it become necessary to remove liquid accumulating in the settling tube 24, this may be readily effected through the blow-off valve 56.

From the foregoing it is obvious that I have provided a method and apparatus for supplying a liquefied petroleum gas such as butane in vapor form to gas consuming appliances and that due to the fact that only liquid is discharged from the bottle or high pressure containers to the vaporizer, the resulting vapors have a substantially uniform calorific value. Therefore the heating appliance operates with a constant valve setting and air mixture, giving a steady and uniform flame.

What I claim and desire to secure by Letters Patent is:

1. A liquefied petroleum gas vaporizing apparatus including, a tank buried under ground to receive earth heat, an expansion and gas storage element in the tank and having an inlet and an outlet, a pressure regulating valve connected with the inlet of the expansion and gas storage element, a supply duct connected with the pressure regulating valve, means connecting the supply duct with a source of liquefied petroleum gas located above ground, and a body of heat transfer liquid in the tank in contact with the regulating valve and expansion and gas storage element to conduct earth heat from the tank to the regulating valve and expansion and gas storage element.

2. A liquefied petroleum gas vaporizing apparatus including, a tank buried under ground to receive earth heat, an expansion and gas storage element in the tank and having an inlet and an outlet, a pressure regulating valve connected with the inlet of the expansion and gas storage element, a supply pipe connected with the pressure regulating valve, means connecting the supply pipe with a source of liquefied petroleum gas located above ground, a body of heat transfer

liquid in the tank in contact with the regulating valve and said expansion and gas storage element to conduct earth heat from the tank to the regulating valve and expansion and gas storage element, a settling tube connected with the outlet of the expansion and gas storage element and submerged in said liquid, a low pressure reducing valve connected with the settling tube, and a gas discharge pipe connected with the low pressure reducing valve.

3. A liquefied petroleum gas vaporizing apparatus including, a tank buried under ground to receive earth heat, an expansion and gas storage coil in the tank and having an inlet and an outlet, a pressure regulating valve connected with the inlet of the expansion and gas storage coil, a supply pipe connected with the pressure regulating valve, means connecting the supply pipe with a source of liquefied petroleum gas located above ground, a body of heat transfer liquid in the tank in contact with the regulating valve and said expansion and gas storage coil to conduct earth heat from the tank to the regulating valve and the expansion and gas storage coil, a settling tube connected with the outlet end of the expansion and gas storage coil and submerged in said heat transfer liquid, a low pressure reducing valve connected with the settling tube, a gas discharge pipe connected with the low pressure reducing valve, and means connected with the discharge pipe exteriorly of the tank for collecting condensate occurring in said pipe.

4. A liquefied petroleum gas vaporizing apparatus including, a tank buried under ground to receive earth heat, an expansion and gas storage coil in the tank having an inlet and an outlet, a pressure regulating valve connected with the inlet of the expansion and gas storage coil, a supply pipe connected with the pressure regulating valve, a liquefied petroleum gas retaining receptacle located above ground, a draw-off tube extending into the receptacle to the bottom thereof for discharging liquefied petroleum gas under pressure of vapor contained in the upper portion of said receptacle, means connecting the draw-off tube with the supply tube, and a body of heat transfer liquid in the tank in contact with the regulating valve and expansion and gas storage coil to conduct earth heat from the tank to the regulating valve and the expansion and gas storage coil, said heat transfer liquid being separate from the liquid hydrocarbon to be vaporized when the apparatus is used.

5. A liquefied petroleum gas vaporizing apparatus including, a tank buried under ground to receive earth heat, an expansion and gas storage coil in the tank having an inlet and an outlet, a pressure regulating valve connected with the inlet of the expansion and gas storage coil, a supply pipe connected with the pressure regulating valve, a liquefied petroleum gas retaining receptacle located above ground, a draw-off tube extending into the receptacle to the bottom thereof for discharging liquefied petroleum gas under pressure of vapor contained in the upper portion of said receptacle, means connecting the draw-off tube with the supply tube, a body of heat transfer liquid in the tank in contact with the regulating valve and the expansion and gas storage coil to conduct earth heat from the tank to the regulating valve and the expansion and gas storage coil, a settling tube connected with the outlet end of the expansion and gas storage coil and submerged in said liquid, a low pressure reducing valve connected with the settling tube, and a gas dis-

charge pipe connected with the low pressure reducing valve.

6. A liquefied petroleum gas vaporizing apparatus including, an expansion and gas storage coil, means supporting said coil within a temperature zone sufficient for supplying heat to effect vaporization of liquefied petroleum gas under a predetermined pressure maintained in said coil, a pressure regulating valve connected with the expansion and gas storage coil for maintaining said predetermined pressure, a source of liquefied petroleum gas connected with the pressure regulating valve, a settling tube located within said heat zone and connected with the expansion and gas storage coil for collecting liquid passing the regulating valve and having a gas outlet, a gas discharge pipe connected with the gas outlet, and a float valve controlling said outlet.

7. A liquefied petroleum gas vaporizing apparatus including, a tank buried under ground to receive earth heat, an expansion and gas storage coil in the tank, a pressure regulating valve connected with the inlet of the expansion and gas storage coil, a supply pipe connected with the pressure regulating valve, means connecting the supply pipe with a source of liquefied petroleum gas located above ground, a body of heat transfer liquid in the tank in contact with the regulating valve and the expansion and gas storage coil to conduct earth heat from the tank to the regulating valve and said expansion and gas storage coil, and a liquid settling tube connected with the expansion and gas storage coil and located in the tank and submerged in said heat transfer liquid.

8. A liquefied petroleum gas vaporizing apparatus including, a tank buried underground to receive earth heat, an expansion and gas storage element in the tank and having an inlet and an outlet, a pressure regulating valve connected with the inlet of the expansion and gas storage element, means connecting the pressure regulating valve with a source of liquid petroleum gas, and a body of heat transfer liquid in the tank in contact with the regulating valve and said expansion and gas storage element to conduct earth heat from the tank to the regulating valve and said expansion and gas storage element.

9. A liquefied petroleum gas vaporizing apparatus including a tank buried underground to receive earth heat, an expansion and gas storage element in the tank, a pressure regulating valve in the tank and connected with the expansion and gas storage element, a liquefied petroleum gas supply pipe connecting the pressure regulating valve with a liquefied petroleum gas supply located above ground, a body of heat transfer liquid in the tank in contact with the regulating valve and said expansion and gas storage element to conduct earth heat from the tank to the regulating valve and said expansion and gas storage element, a discharge pipe connected with the expansion and gas storage element, and a low pressure regulating valve interposed between the storage element and said discharge pipe.

10. A liquefied petroleum gas vaporizing apparatus including a tank buried underground to receive earth heat and having a body of heat transfer liquid therein, an expansion and vaporizing coil in the tank in heat exchange relationship with the liquid contained in said tank, a pressure reducing valve within the confines of the tank in position to receive heat from said

liquid, said valve being connected with the expansion and vaporizing coil, means for conducting liquefied petroleum gas to the pressure reducing valve under pressure, a service conduit means connected to the expansion and vaporizing coil, and a low pressure regulating valve in said conduit.

11. In a liquefied petroleum gas system, the combination of a tank having a liquid therein and receiving heat from the earth, a regulator disposed in heat exchange relationship with the liquid contents of the tank, conduit means for supplying the regulator with a liquefied petroleum gas in its liquid phase, a second conduit means connected to the regulator and extending from said regulator to a point of use including a coil submerged in said liquid contents, and means for insulating the regulator from heat exchange with atmosphere.

20 12. A method of dispensing liquefied petroleum gas as a dry gas including storing a quantity of liquefied petroleum under pressure at above ground temperature, withdrawing the liquefied petroleum from storage, vaporizing the withdrawn liquefied petroleum gas by reducing the pressure of the liquefied petroleum gas while in direct heat exchange contact with the upper portion of a body of heat exchange liquid which is independent of the stored liquefied petroleum gas and warmed directly and solely by earth heat for converting the withdrawn liquefied petroleum to a gas without mixture with said heat exchange liquid, storing the gas within the body of heat exchange liquid without mixture with said heat exchange liquid, drawing on the stored gas as needed, and reducing the pressure of the gas withdrawn from said storage.

25 13. A method of dispensing liquefied petroleum gas as a dry gas including storing a quantity of liquefied petroleum under pressure at above ground temperature, withdrawing the liquefied petroleum from storage, vaporizing the withdrawn liquefied petroleum by reducing the pressure of the liquefied petroleum gas while in direct heat exchange contact with the upper portion of a body of heat exchange liquid warmed directly and solely by earth heat for converting the withdrawn liquefied petroleum to a gas without mixture with said heat exchange liquid, storing the gas within the body of heat exchange liquid without mixture with said heat exchange liquid, drawing on the stored gas as needed, settling out any unvaporized foreign liquid entrained with the withdrawn gas, and reducing the pressure of the gas withdrawn from said storage.
